UNITED STATES PATENT OFFICE.

FRANCIS C. SANFORD, OF BRIDGEPORT, CONNECTICUT, ASSIGNOR TO THE CINCINNATI MILLING MACHINE COMPANY, OF CINCINNATI, OHIO, A CORPORATION OF OHIO.

CENTERLESS GRINDING MACHINE FOR TAPERING DRILLS AND THE LIKE.

Application filed November 17, 1922. Serial No. 601,643.

- This invention pertains to centerless grinding machines, which may be described as comprising a grinding and a control wheel, and an intermediate work support, 5 the grinding wheel moving at a high surface speed where it contacts with the work lying upon the work-rest, and the control wheel moving at a relatively low speed and in the opposite direction where it makes contact 10 with the opposite side of the work. In its preferred embodiment the centerless grinding machine employs wheels of true cylindrical form, with their peripheral faces opposed and acting directly upon the work lying between their proximate peripheries, though other forms of opposed grinding surfaces are well known in the centerless grinding art. With peripherally opposed cylindrical grinding and control 15 wheels having their axes adjusted to common plane there is formed between them a throat or passage of progressively narrowing width from a point above or below the common plane of their axes, toward said 20 plane. This narrowing form of throat is availed of in the present invention, as will later appear, and is hence noted at this point. It renders possible, through the use of simple work-supporting and feeding devices, 25 the attainment of the primary object of this invention, which is to produce a simple and efficient machine for grinding bodies or articles to true circular cross section and to tapered form.
- A further object is to provide a machine for tapering drills and the like including a feed slide upon the machine and a rest for the work or article to be tapered upon the feed slide, the feed slide being angularly adjustable with respect to a grinding wheel to be 30 capable of imparting the proper and preferred lift to the article as it is fed forwardly, and the work rest being angularly adjustable with respect to the grinding wheel and feed slide to cooperate with the feed slide in presenting the article to the grinding wheel at proper and preferred angle to accurately obtain the exact taper desired.
- A still further object is to provide in a 35 machine of the present character, a feed slide and a work rest adapted to be adjusted angularly and set with respect to each other and with respect to a grinding wheel to be
- capable of cooperating in accurately tapering an article an exact and predetermined amount.
- Another object is to provide in a centerless cylindrical grinding machine, an adjustable feed for uniformly lifting an article as it is fed between and past a grinding and a drive wheel, and an adjustable rest associated with the feed for disposing the work or article at proper angle to the axis of the grinding wheel, whereby the feed and rest can be nicely adjusted to predetermined positions and set to be capable of presenting the article to the grinding wheel in such manner that (1) the forward and rearward, or large and small, ends of the article will have the desired diameters at the moment they pass off of the grinding wheel; and (2) the peripheral face of the article between its ends will be accurately tapered from end to end of the article.
- And yet another object is to provide a 75 grinding machine consisting of a grinding and a control wheel arranged opposite each other, the axial lines of said wheels being parallel and their working faces being concentric with their axes, of a vertically, angularly adjustable feed slide for uniformly advancing and lifting an article to be tapered as the article is fed to and past the working faces of said grinding and control wheels to engage said faces in a plane below the axes of the grinding and control 80 wheels, and of a vertically, angularly adjustable rest associated with the feed slide for disposing the article at proper angle to the axes of the grinding and control wheels, the adjustable work rest being adapted to cooperate with the feed slide in presenting the article to the grinding wheel in that manner previously ascertained to be most suitable for the particular article to be 85 tapered.
- With the above and other objects in view, the invention comprises the construction, arrangement and combination of parts as now to be fully described and as hereinafter to 90 be specifically claimed, it being understood that the disclosure herein is merely illustrative of the principles of the invention and meant in no way in a limiting sense, changes in details of construction and arrangement of parts being permissible so long

as within the scope of the appended claims.

In the accompanying drawing forming a part of this specification.

Fig. 1 is a plan view of a machine dis-

closing the principles of the invention;

Fig. 2 is a sectional view on line 2—2 in

Fig. 1;

Fig. 3 is a perspective view of the feed bracket, feed slide, and work rest;

10 Figs. 4 and 5 are diagrammatic views better disclosing principles of the invention; and

15 Fig. 6 is a diagrammatic view, corresponding with the showing of Fig. 5, suggesting the mode of operation of the machine when the work rest is disposed at an angle different from the angle of the rest of Figs. 1 to 5.

With respect to the drawing and the numerals of reference indicated thereon, 10 20 denotes the machine frame, 11 a grinding wheel upon a preferably horizontally arranged shaft 12 having a pulley 13 and journaled in a bearing 14 on the frame, and 15 denotes a control wheel arranged oppo- 25 site the grinding wheel on a parallel shaft 16 having a pulley 17 and mounted in bearings 18, 19 of a control wheel carrier 20 which is desirably longitudinally adjustable on the frame, whereby the control wheel 30 can be adjusted toward and from the grinding wheel, numeral 21 designating, generally, mechanism including a hand wheel for im- parting longitudinal movement to the control wheel.

35 The working faces of the grinding and control wheels are parallel and may be spaced any suitable distance apart, depending upon the dimensions of the particular article being tapered. Obviously, the pul- 40 leys 13 and 17 are to receive belts for rotating the grinding and control wheels at suitable speeds.

45 Numeral 22 denotes a carrier for the feed bracket 23 and feed slide 24, this carrier being situated between and beneath the grinding and control wheels and being secured to the frame to be longitudinally adjustable thereon, as denoted at 25, whereby the carrier 22 can be moved to its proper working 50 position on the frame beneath the grinding and control wheels.

55 As disclosed, the feed bracket 23 has integral feet or lugs 26 receiving screw bolts 27 securing the feed bracket to the carrier 22, and includes spaced apart and parallel ribs 28, arranged transversely of the frame and parallel with the axes of the grinding and control wheels. A slide support 29, ar- 60 ranged between the ribs 28, is pivoted at the lower portion of its rearward end 30 to the parallel ribs and is provided at its forward end with a threaded opening receiving a lifting screw 31 engaging the bracket 23 whereby the slide support can be arranged to have any preferred inclination or slope.

The feed slide 24 may have a dove tail fit upon the slide support, as denoted at 32, to permit reciprocation thereon, and a work rest 33 may be associated with the feed slide in any manner to be adjustable vertically to 70 have any angle with respect to the feed slide and grinding wheel. As disclosed, the lower portion of the forward end of the work rest is pivoted to the slide as at 34, while the rearward portion thereof has an opening to 75 receive a screw 35 engaging the feed slide and having adjusting and locking nuts 36 above and below the opening. The work rest includes a seat 37 for an article A, such as a drill, to be tapered.

80 Numeral 39 represents a hand piece whereby the feed slide can be actuated to move transversely of the frame, although the feed slide could be manipulated in some other convenient manner.

85 In the drawings the axes of the two wheels 11 and 15 are shown in the same horizontal plane, and the slide support 29 and work rest 33 are shown as both adjustable in a vertical plane, or in a plane at a right angle 90 to that in which the wheel axes lie. If the plane of the axes be other than horizontal, as it may be, the plane of adjustment of the slide support 29 and work rest 33 will be correspondingly shifted from the vertical, or 95 will remain perpendicular to the plane of the wheel axes.

100 In Fig. 2 the seat 37 is shown horizontally arranged, parallel with the axes of the grinding and control wheels and at considerable distance below said axes. In Figs. 4 and 5 I have diagrammatically disclosed the manner in which a cylindrical article so situated would be tapered as the feed slide advances and lifts to move the article to and beyond the grinding wheel. Up to that point where the article starts to move beyond the wheel, as denoted at *a* in Figs. 4 and 5, its center line is horizontal, or parallel with the axes of the grinding and control wheels. When the article has been completely removed from the grinding wheel, as at *b* in Figs. 4 and 5, its center line has shifted vertically to be a trifle below the horizontal, it being understood that the article 110 at *b* is also beneath the centers of the grinding and control wheels.

115 In Fig. 6 I have diagrammatically disclosed an article to be tapered, as at *a'*, considerably below the axes of the grinding and control wheels, as when arranged on a seat allowing proper engagement of the article with the grinding and control wheels, but 120 out of parallel with the axes of said grinding and control wheels. As the article shown advances and lifts, to the position *b'*, off of the grinding wheel and beneath the centers of the grinding and control wheels, the center line moves nearer to the horizontal.

125 The feed slide and the work rest can be 130

angularly adjusted vertically to have any angular relations with respect to the axes of the grinding and control wheels and with respect to each other to make possible the 5 production of any tapering result desired. The double adjustment tends toward exactness and accuracy, the angularly adjustable feed slide being more sensitive for the adjustment looking toward the predetermined 10 size of the forward or large end of the article being tapered, the angularly adjustable work rest being more sensitive for the adjustment looking toward the predetermined size of the rearward or small end of the article, and both feed slide and work rest 15 when adjusted cooperating in the machine to ensure the predetermined taper desired in the finished article.

It will be apparent that the angle of feed 20 and the angle of the rest can be adjusted to obtain any taper, so long as the article being tapered remains below the centers of the grinding and control wheels, the relative positions of the parts as illustrated and described being merely for the purpose of explanation of the invention.

Having thus fully described the invention, what I claim as new and desire to secure by Letters Patent is:

30 1. A grinding machine comprising a grinding wheel and a control wheel arranged in peripheral opposition; a feed slide adjacent and movable across the peripheral face of the grinding wheel; and a work rest 35 mounted upon said slide, the work rest and the slide being independently and relatively adjustable to different degrees of angularity in a common plane perpendicular to the common plane of the wheel axes.

40 2. In a machine of the character described, a grinding wheel and a control wheel in peripheral opposition; a feed slide movable across the peripheral face of the grinding wheel in a plane perpendicular to the common plane of the wheel axes, said slide being adjustable to varying angularity to said plane of the wheel axes; and a work rest mounted upon said slide.

50 3. In a machine of the character described, a grinding wheel and a control wheel in peripheral opposition; a feed slide movable across the peripheral face of the grinding wheel in a plane perpendicular to the common plane of the wheel axes, said slide being adjustable to varying angularity to said plane of the wheel axes; and a work rest mounted upon said slide and adjustable to varying angularity with reference to the slide, and in the same plane as the slide.

60 4. In a machine of the character described, a grinding wheel having each point in its working face arranged at the same distance from its axis, a control wheel with similar working face arranged opposite said grinding wheel, the axes of said wheels being

parallel, a feed slide arranged beneath, between and transversely of said wheels, said feed slide being adjustable angularly in a plane parallel with the lines of both axes and perpendicular to a plane passing through 70 said axes, and a work rest upon said feed slide, said work rest being adjustable angularly in the same plane as is the feed slide.

5. In a machine of the character described, a grinding wheel having a substantially 75 horizontal axis and a working face every point of which is equidistant from said axis; a slide arranged adjacent said working face in a vertical plane parallel with the vertical plane of the grinding wheel axis, and vertically adjustable in its own plane to desired angularity to the grinding wheel axis; and a work rest mounted upon said slide and adjustable relatively thereto in the same plane as the slide, to vary its angularity relative to the slide, said work rest having a 85 seat to receive and support the work and to hold the same against independent axial movement.

6. In a machine of the character described, 90 a grinding wheel having a substantially horizontal axis and a working face every point in which is equidistant from said axis; an inclined feed slide arranged adjacent said working face of the wheel and movable 95 transversely across the same in a plane parallel to the vertical plane of the wheel axis; and a work rest mounted upon and movable with the slide, said rest being angularly adjustable relatively to the slide, in a vertical 100 plane, and being provided with a work seat to receive and support the work and to hold the same against independent axial movement.

7. A machine of the character described, 105 comprising a grinding wheel having a horizontal axis and a working face each point of which is spaced at the same distance from said axis, a control wheel with similar working face arranged opposite said grinding 110 wheel, the axes of said wheels being parallel, an inclined feed slide support arranged adjacent said wheels, a feed slide upon said support and adapted to traverse the plane of said grinding and control wheels, said feed 115 slide lying in a plane which is perpendicular to the plane of said wheels, and an adjustable work rest upon said feed slide, said work rest being angularly adjustable in a vertical plane and having a work seat lying in a plane perpendicular to the plane of 120 said grinding and control wheels, whereby said seat can present the full length of an article being tapered to both of said wheels as said feed slide advances and lifts.

8. A centerless grinder, comprising a support lying in a plane intermediate the proximate faces of the grinding and control wheels, and having its upper face inclined relatively to the common plane of the axes

of said grinding and control wheels; and a slide engaging and movable upon said support and provided with a work-rest having a seat to receive the article to be ground, said slide being longitudinally movable, whereby it is adapted to move the article laterally and progressively into the narrowing throat between the grinding and control wheels and to carry the article progressively out of contact with the grinding and control surfaces as grinding progresses.

9. A centerless grinder, comprising a support lying in a plane intermediate the proximate faces of the grinding and control wheels, and capable of adjustment to varying relation to the common plane of the axes of said grinding and control wheels; and a slide engaging and movable upon said support and provided with a work-rest having a seat to receive the article to be ground, said slide being longitudinally movable, whereby it is adapted to move the article laterally and progressively into the narrowing throat between the grinding and control wheels, and to carry the article progressively out of contact with the grinding and control surfaces as the grinding progresses, the rate of lateral feed being determinable by the degree of inclination of the slide.

10. A centerless grinder, comprising a support lying in a plane intermediate the proximate faces of the grinding and control wheels and having its upper face oblique to the common plane of the axes of said grinding and control wheels; a slide engaging and movable upon said support; and a work-rest pivotally mounted upon said slide and

having a seat to receive the article to be ground, the slide and work-rest being longitudinally movable, whereby the article ground is moved laterally and progressively into the narrowing throat between the grinding and control wheels and carried progressively out of contact with the grinding and control surfaces as the grinding progresses, the adjustment of the pivoted work-rest serving to determine the degree of taper effected by the grinding.

11. A centerless grinder, comprising a support lying in a plane intermediate the proximate faces of the grinding and control wheels and pivoted for adjustment in a plane perpendicular to the common plane of the axes of the grinding and control wheels; a slide engaging and movable upon said support; and a work-rest pivotally mounted upon said slide and having a seat to receive the article to be ground, the slide and work-rest being longitudinally movable, whereby the article to be ground is moved laterally and progressively into the narrowing throat between the grinding and control wheels and is carried progressively out of contact with the grinding and control surfaces as the grinding progresses, and the adjustment of the pivoted work-rest serving to determine the degree of taper effected by the grinding regardless of the inclination of the slide and its support and the consequent rate of lateral feed of the work.

Signed at Bridgeport, in the county of Fairfield, and State of Connecticut, this 14th day of November, A. D. 1922.

FRANCIS C. SANFORD.
